UNITED STATES PATENT OFFICE.

ERASTUS E. WINKLEY, OF LYNN, MASSACHUSETTS.

INTERNAL-COMBUSTION ENGINE.

1,131,099.

Specification of Letters Patent.

Patented Mar. 9, 1915.

Application filed May 4, 1906. Serial No. 815,140.

To all whom it may concern:

Be it known that I, ERASTUS E. WINKLEY, a citizen of the United States, residing at Lynn, in the county of Essex and State 5 of Massachusetts, have invented certain new and useful Improvements in Internal-Combustion Engines; and I do hereby declare the following to be a full, clear, and exact description of the invention, such as will 10 enable others skilled in the art to which it appertains to make and use the same.

The present invention relates to improvements in internal combustion engines.

In internal-combustion engines, as at present more commonly constructed, the entire volume of explosive mixture used at each working stroke of the piston is that which is drawn into the cylinder by the preceding suction stroke, or, in a two-cycle engine, 15 drawn into the crank case during the preceding compression stroke of the piston. This charge is ignited at, or shortly before, the commencement of the working stroke, and during this stroke its pressure, which is 20 drawn into the cylinder by the preceding suction stroke, or, in a two-cycle engine, drawn into the crank case during the preceding compression stroke of the piston. This charge is ignited at, or shortly before, the commencement of the working stroke, and during this stroke its pressure, which is 25 at first as great as the working parts of the engine are calculated to bear, falls rapidly, on a curve approximating an adiabatic curve, so that near the end of the working stroke, when the exhaust commences, the 30 working pressure has fallen to 50 pounds or less per square inch. This mode of operation results in a mean effective pressure much less than the maximum pressure of the explosion, and during most of the 35 expansion stroke the engine is working under a pressure much lower than the working parts can safely bear.

One object of the present invention is to increase the efficiency of internal-combustion engines by arranging and constructing them in such a manner that a high working pressure is maintained through a greater portion of the working stroke than in engines of the ordinary character.

Another object of the invention is to produce an engine for use where the power demand varies widely, as, for example, in automobiles, the engine operating economically and in a normal manner so long as a 45 moderate amount of power is demanded, but having provision for substantially increasing its power either automatically or at the will of the operator when an extraordinary amount thereof is required.

To the above ends the invention contemplates the use, in connection with the ordi-

nary working parts of an internal-combustion engine operating in the ordinary, or any suitable, manner, to induce, compress, and fire an explosive or combustible charge, of auxiliary devices for exploding and introducing into the working cylinder, during the working stroke of the piston, an additional supply of motive fluid to maintain the initial high working pressure during a greater part of the working stroke, so that the power of the engine is greatly increased without increase in the dimension of the cylinder or the strength of the working parts.

Other objects and features of the invention will be noted in connection with the description of the illustrated embodiment of the invention.

In the drawings Figure 1 is a front elevation, partly in section, of an internal-combustion engine embodying the present invention; Fig. 2 is a left side elevation partly in section; Fig. 3 is a right side elevation with parts omitted; Fig. 4 is a front elevation of a portion of the cam mechanism and the ignition-timing devices; Fig. 5 is a detail front elevation of the exhaust cams and part of the cam mechanism; Fig. 6 is a detail plan view of the ignition-timing devices; and Fig. 7 is a sectional detail view of a part of the ignition-timing devices.

In the illustrated embodiment the invention is applied to a 4-cycle internal-combustion engine. The engine is provided with a working cylinder 1 in which a piston 2 reciprocates. The upper end of the cylinder is integral with a combustion chamber 3 in which an explosive charge is compressed by the piston and exploded in the ordinary manner. The combustion chamber is provided with the ordinary inlet and exhaust valves 4 and 5, shown in Fig. 1, the exhaust valve being actuated in the usual manner by a spring and a cam mechanism.

The lower end of the cylinder 1 is constructed to operate, in conjunction with the piston, as a pump, being closed for this purpose with a head 6 provided with a stuffing box 7 through which passes a piston rod 8 connected with the piston. The piston rod is connected also with a cross-head 9 sliding in guides on the engine frame, and a connecting rod 10 connects the cross-head with a crank 11 on the crank shaft 12 of the engine. The lower end of the cylinder is connected, through a port 13, and a pipe 14, with the pipe 15 through which explosive mixture is

supplied to the engine, the pipe 15 being connected at its lower end with any suitable device for supplying an explosive mixture. The pipe 15 is also connected with the inlet valve 4, so that at each stroke of the piston in the cylinder explosive mixture is drawn into one end or the other of the cylinder. The pipe 14 is provided with an automatic puppet valve 16 which prevents the return of mixture from the cylinder, and it is also provided with a manually-operable stop cock 17. In addition to the main combustion chamber 3 above described, an auxiliary combustion chamber 18 is provided, this chamber being connected with the lower end of the cylinder by a transfer passage 19 provided with an automatic puppet valve 20. The mixture drawn into the lower end of the cylinder by the piston on its upward or in-stroke is compressed, during the succeeding out-stroke of the piston, and passes through the transfer passage 19 and the valve 20 into the auxiliary combustion chamber 18, its return upon the succeeding in-stroke of the piston being prevented by the puppet valve 20. The auxiliary combustion chamber 18 is connected through a port 21 with the cylinder at a point somewhat below the uppermost position of the piston 2, and this port is controlled by a valve 22 having a stem 23 provided with a collar 24 engaged by a compression spring 25, which normally holds the valve 22 closed so as to interrupt communication between the auxiliary combustion chamber and the cylinder. The lower end of the stem 23 is engaged by a push rod 26 guided in the frame of the engine. The lower end of the push rod rests upon an arm 27 fixed to a rock shaft 28 slid-
ingly mounted in lugs 29 on the frame of the engine. The rock shaft 28 carries also an arm 30 on which is journaled a cam roll 31 (see Figs. 1, 2 and 5) which engages a cam 32 fixed to the half-speed shaft 33 of the engine. The shaft 33 carries also a gear 34 meshing with a pinion 35 on the crank shaft 12, by which the shaft 33 is rotated at half the speed of the crank shaft, in the usual manner. The shaft 33 carries the exhaust cam 36 by which the exhaust valve 4 is operated in the usual manner, the movements being communicated from the cam 36 to the valve by means of mechanism similar to that by which the valve 22 is operated (see Fig. 1) and including a rock-shaft 37, a push rod 38, a lever 39 pivoted at 40 on the top of the engine, and a cap 41 engaged by the forked end of the lever 39 and resting upon the upper end of the exhaust valve stem. The exhaust valve is normally held closed by a spring 42 in the ordinary manner.

Igniting devices are provided, both for the main combustion chamber 3 and for the auxiliary combustion chamber 18, these devices comprising spark plugs 43 and 44 re-

spectively, together with a suitable source of electricity connected with the spark plugs and operating in the ordinary manner to produce sparks at the proper time. The times at which the ignition is effected are determined by the timing devices, shown particularly in Figs. 1, 4, 6 and 7. The half-speed shaft 33 carries a disk 45 of insulating material, provided with two metallic contact pieces 46 and 47. Two contact springs 48 and 49 bear against the disk 45 in position to be engaged by the contact pieces 46 and 47 respectively during the rotation of the disk 45. The spring 48 is connected with the electrical devices by which the spark plug 44 in the auxiliary combustion chamber is operated, while the spring 49 is connected with the electrical devices for operating the spark plug in the main combustion chamber, and the relative positions of the springs and the contact pieces 46 and 47 are such that as the disk 45 rotates in the direction of the arrow (Fig. 4) an electrical contact will be made, first between the contact piece 47 and the spring 49, and, shortly afterward between the contact piece 46 and the spring 48, so as to ignite first the charge in the main combustion chamber, and then the charge in the auxiliary combustion chamber. These timing devices operate to distribute the current to the induction coils or other devices by which the spark plugs are operated, and as the construction of such devices is familiar they are not here shown. The contact springs are fixed to stems 50 which pass through insulating bushings 51 seated in base plates 52 engaging slots 53 in brackets 54 and 55, the slots 53 being curved concentrically with the half-speed shaft 33. Nuts 56 on the stems 50 serve to fix the parts above described together. By this arrangement the contact springs 48 and 49 may be adjusted angularly about the shaft 33 to vary the times at which contacts are made and the ignition devices are operated, it being necessary for this purpose only to loosen the nuts 56 and move the base plates 52 one way or the other in the slots 53.

The bracket 54 is mounted in fixed position upon the frame of the engine, but the bracket 55 is mounted to move longitudinally with respect to the half-speed shaft 33, being supported for this purpose by means of two lugs 58 and 59. The lug 58 slides freely upon a pin 60 on the frame of the engine, and the lug 59 is embraced between the lever 30 and collar 62 fixed to the rock shaft 28. (See Figs. 1 and 2). The rear end of the rock shaft 28 carries a grooved collar 63, engaged by a pin 64 in a hand lever 65 pivoted at 66 on the frame of the engine. The hand lever is secured in position by a binding screw 67 engaging a slotted sector 68 (see Figs. 2 and 3). This arrangement is such that by releasing and

moving the hand lever 65 the rock shaft 28 may be moved longitudinally in its bearings on the frame of the engine, carrying with it the cam lever 30 and also the bracket 55. As 5 shown in the drawings the hand lever is in such position that these parts are operative, the cam roll 31 engaging the cam 32 and the bracket 55 being in such position that the contact spring 48 carried thereby properly 10 engages the insulating disk 45 and the contact piece 46, but when the hand lever is moved to its opposite position, that is, to the left as shown in Fig. 27, the rock shaft 28 moves longitudinally in the same direction, 15 and the cam roll 31 and the contact spring 48 are thereby carried out of operative engagement with the cam and the contact piece, so that the valve 22 and the igniting device for the auxiliary combustion chamber 20 cease to operate. The stop cock 17 in 20 the inlet pipe 14, Fig. 1, is closed by the operative at the same time, and the engine then operates as an ordinary four-cycle engine, combustion occurring only in the main combustion chamber, while the piston merely 25 works against a vacuum in the lower end of the cylinder.

When it is desired to obtain the full power of the engine the stop cock 17 is opened and 30 the hand lever moved to the position of the drawings, so as to throw the auxiliary combustion chamber and its igniting devices into operation, and the engine then operates as follows:—Supposing the parts to be in 35 the position of the drawings, with the engine at the beginning of its cycle of operations, upon the descent of the piston a charge of explosive mixture is drawn in through the inlet valve 4 and simultaneously 40 the contents of the cylinder below the piston, consisting of explosive mixture previously drawn into the cylinder through the port 13, is compressed and forced through the transfer passage 19 into the auxiliary 45 combustion chamber 18, the latter being thereby filled with explosive mixture under considerable pressure. Upon the succeeding upward or instroke of the piston the space below the piston is again filled with explosive 50 mixture through the port 13, and the mixture above the piston is compressed into the main combustion chamber 3. Just before the piston reaches the limit of its stroke contact piece 47 engages the contact spring 55 49, as shown in Fig. 4, and thereby causes the spark plug of the main combustion chamber to operate and fire the charge in the usual manner. The piston then commences its out-stroke, and during the first 60 part of the out-stroke the contact piece 46 engages the contact spring 48 and causes the spark plug for the auxiliary chamber to operate and fire the charge in the auxiliary chamber. At about the same time the cam 65 32 engages the cam roll 31, and through the

mechanism above described the valve 22 is lifted, affording free communication through the port 21 from the auxiliary combustion chamber 18 to the cylinder. At this time, or shortly thereafter, the piston in its outward 70 stroke uncovers the port 21, and the contents of the auxiliary combustion chamber flow into the cylinder, thereby raising the pressure in the cylinder above the point to which it has fallen owing to the descent of the piston, and the piston then continues on its out-stroke to the bottom of the cylinder, the exhaust valve being opened shortly before it reaches the bottom in order to permit the burnt gases to escape. During this working 80 stroke of the piston the explosive mixture below the piston is compressed, and as soon as the pressure beneath the piston has risen sufficiently to equal that in the auxiliary combustion chamber and the upper part of 85 the cylinder the explosive mixture begins to flow through the valve 20 into the auxiliary chamber. During the last part of the working stroke of the piston, when the exhaust valve is open and the pressure in the cylinder and the auxiliary chamber has fallen to atmospheric pressure, the mixture remaining below the piston flows freely through the valve 20 into the auxiliary chamber and thence through the port 21 into the cylinder. 90 In this manner the burnt gases remaining in the auxiliary chamber are swept out by a fresh mixture, and also a quantity of fresh mixture is delivered to the cylinder. Upon the succeeding instroke of the piston, during 100 which the exhaust valve 5 is held open, the burnt gases are discharged from the cylinder, and the explosive mixture delivered to the cylinder from the auxiliary chamber dilutes the contents of the main combustion chamber 3 and partially or entirely displaces the burnt gases which would otherwise remain therein, so that the engine operates with a purer explosive charge than when it 105 is running as an ordinary four-cycle engine, and that the power of the engine is thereby further augmented.

Owing to the reinforcement of the working charge in the cylinder by the auxiliary combustion chamber the power of the engine is much greater, when operated in the manner above described, than that of the ordinary four-cycle engine of the same dimensions. This makes the engine particularly useful for automobiles and other purposes where an engine of great power and light weight is required, particularly where the amount of power required varies widely from time to time, as in an automobile. It 115 has previously been necessary, in such a connection, to use an engine of sufficient power to meet the utmost demands, such as are encountered in climbing hills, and consequently such engines, when operating under 120 normal conditions, are running under only 125 130

a fraction of their full load, with a resulting loss in economy which is well recognized by those skilled in the art. The present invention, however, is adapted to 6 operate not only with a power much greater than its normal output when the necessity arises but it also operates, under normal conditions, under a full or substantially full load, with the economy incident there- 10 to, owing to the fact that when the auxiliary devices are thrown out of operation the engine operates as an ordinary internal-com- bustion engine; and thus, owing to the flexi- 15 bility resulting from the use of the auxiliary devices, a comparatively small engine oper- ating normally under substantially full load may be used in place of a larger engine oper- ating normally under reduced load.

A further advantage of the invention lies 20 in the facility with which it may be made self-starting; there are twice as many residual charges remaining in the engine after stopping as in the ordinary engine of the same number of cylinders and it is further 25 to be noted that the auxiliary chambers will retain compression much longer than the cylinders as there are no pistons therein to afford opportunity for leakage. When the engine is to be used as self-starting the 30 auxiliary devices are thrown into operation just before stopping the engine, and the engine is then stopped by switching off the electricity, whereby the combustion chambers are left charged with explosive mixture. 35

Although the invention has been illus- trated as embodied in an engine operating on the ordinary Otto or four-cycle principle, it is not limited to an engine of this char- 40 acter but may be embodied in internal-com- bustion engines of other types.

The applicant is aware that it has been previously proposed to provide an engine with a plurality of combustion chambers 45 into which explosive charges are compressed and in which they are successively ignited, but in such previously-proposed devices the charges have not been formed independ- 50 ently, that is to say, they have been formed by diverting a part of the charge which would normally be compressed into the main combustion chamber by the piston, so that instead of augmenting the power of the engine the use of such devices as have been 55 previously proposed would result in a de- crease in the power of the engine, owing to the fact that the entire amount of explosive mixture drawn into the cylinder above the piston is not utilized as effectively as in the 60 ordinary engine, and owing to the further fact that in such devices as have been pre- 65 viously proposed the charges in the several combustion chambers have not been ignited by independent igniting devices operating 65 to ignite them sufficiently early to cause the

pressure to rise to its fullest extent before the contents is discharged into the cylinder, but have relied upon the ignition of the charges in the several combustion chambers by the flame in the cylinder coming into contact with the charges successively as the piston uncovers the ports to the several combustion chambers.

The invention is not limited in general 70 to the details of construction and operation 75 of the illustrated embodiment but may be embodied in other forms broadly defined in the claims.

Where in the claims the phrase "inde- 80 pendently forming a plurality of charges" is used, this is to be understood as referring 85 to the formation of the charges independ- ently of each other as distinguished from the formation of a single charge which would normally be compressed into the main combustion chamber and the splitting up of said main charge into a plurality of smaller charges.

Having now described the invention, what 90 is claimed is:

1. An internal-combustion engine, having, 95 in combination, a working cylinder, a piston therein, means for igniting an explosive charge in the cylinder, and means for igniting and thereafter introducing a supple- 95 mental charge into the cylinder during the working stroke of the piston; substantially as described.

2. An internal-combustion engine, having, 100 in combination, a working cylinder, a piston therein, means for igniting an explosive charge in the cylinder, and means for igniting and thereafter introducing a supple- 105 mental charge into the cylinder subsequently to the ignition of the charge in the cylinder and during the working stroke of the piston, substantially as described.

3. An internal-combustion engine, having, 110 in combination, a working cylinder, a piston therein, and means for forming and inde- 115 pendently compressing a plurality of sepa- rate charges, and for imparting them suc- cessively to the cylinder during the same working stroke of the piston, substantially as described.

4. An internal-combustion engine, having, 120 in combination, a working cylinder, a piston therein, a plurality of combustion chambers connected with the cylinder, means for sup- 125 plying the chambers with explosive mix- ture, and an igniting device in each cham- ber, substantially as described.

5. An internal-combustion engine, having, 125 in combination, a cylinder, a piston therein, an auxiliary combustion chamber, a connec- 130 tion between the chamber and the cylinder for conducting the ignited charge to the cylinder, a cam-actuated valve controlling said connection, means for supplying explosive mixture to the cylinder and the auxiliary 130

combustion chamber, and igniting devices for igniting separately the mixture in the cylinder and the auxiliary chamber, substantially as described.

- 5 6. An internal-combustion engine, having, in combination, a working cylinder, a main combustion chamber communicating therewith, a piston in the cylinder, an auxiliary combustion chamber communicating with the cylinder at a point outside of the inmost position of the piston, means for supplying explosive mixture to the main and auxiliary combustion chambers, and separate igniting devices for the chambers, substantially as described.

- 10 7. An internal-combustion engine, having, in combination, a cylinder, a piston therein, an auxiliary combustion chamber connected with the cylinder at a point outside of the inmost position of the piston, a cam-actuated valve controlling the connection between the cylinder and the auxiliary combustion chamber, and means for supplying explosive mixture to the cylinder and chamber, substantially as described.

- 15 8. An internal-combustion engine, having, in combination, a cylinder provided with an inlet port and an exhaust port, a piston in the cylinder, an auxiliary combustion chamber connected with the cylinder, means for introducing an explosive charge into said chamber and igniting it, and means for interrupting communication between the chamber and the cylinder during the charge-compressing stroke of the piston in the cylinder, substantially as described.

- 20 9. An internal-combustion engine, having, in combination, a cylinder, a main combustion chamber connected with the inner end of the cylinder, an auxiliary combustion chamber connected with each end of the cylinder, means for supplying explosive mixture to each end of the cylinder, and a piston in the cylinder acting to draw in mixture and compress it at each end of the cylinder to supply the combustion chambers, and means for igniting the compressed charges, substantially as described.

- 25 10. An internal-combustion engine, having, in combination, a cylinder, a main combustion chamber connected with one end thereof, an auxiliary combustion chamber connected with the other end, means for introducing air into each end of the cylinder, a piston in the cylinder acting to compress the air in each end thereof and to force it into the combustion chambers as part of an explosive charge therein, and separate ignition devices in the two combustion chambers, substantially as described.

- 30 11. An internal-combustion engine, having, in combination, a cylinder, a piston therein, auxiliary devices for igniting and introducing into the cylinder a reinforcing charge during the expansion stroke of the

piston, and means for throwing the auxiliary devices into and out of operation during the continued operation of the engine, substantially as described.

35 12. An internal-combustion engine, having, in combination, a cylinder, a piston therein, a main combustion chamber connected with the cylinder, an auxiliary combustion chamber connected with the cylinder, and means for admitting air to the auxiliary chamber operating alternately to form an explosive charge therein and to sweep the products of combustion therefrom, substantially as described.

40 13. A four-cycle internal-combustion engine, having, in combination, a cylinder closed at each end, a piston therein, inlet valves for admitting air to each end of the cylinder, an auxiliary combustion chamber communicating with the inner part of the cylinder and having a valved connection with the outer end of the cylinder to receive air therefrom at each outstroke of the piston, and means for igniting the contents of the auxiliary combustion chamber at alternate outstrokes of the piston, substantially as described.

45 14. An internal-combustion engine, having, in combination, a cylinder, a piston therein, an auxiliary combustion chamber, means for supplying explosive mixture to the cylinder and to the auxiliary combustion chamber, igniting devices for igniting separately the mixture in the cylinder and in the auxiliary chamber, and connections between the auxiliary chamber and the cylinder to conduct the ignited mixture from the chamber to the cylinder, substantially as described.

50 15. An internal-combustion engine of the compression type, having, in combination, a cylinder, a piston therein, means for supplying a full charge to the cylinder, and auxiliary devices for supplying an additional charge during the working stroke of the piston, substantially as described.

55 16. An internal-combustion engine of the compression type, having, in combination, a cylinder, a piston therein, means for normally supplying a full charge to the cylinder, auxiliary devices for supplying an additional charge during the working stroke of the piston, and means for throwing the auxiliary devices into and out of operation, substantially as described.

60 17. An internal combustion engine, having, in combination, a cylinder, a piston therein, an auxiliary combustion chamber, a connection between said chamber and the cylinder, a valve controlling said connection, a mechanism operative at the will of the operator for actuating said valve, and means for supplying explosive mixture to the cylinder and to said chamber, substantially as described.

18. An internal combustion engine, having, in combination, a cylinder, a piston therein, an auxiliary combustion chamber, a port in the cylinder wall located to be uncovered by the piston during its power stroke, a connection between the chamber and the port, a valve controlling the connection, mechanism for controlling the valve, and means for supplying explosive mixture to the cylinder and chamber, substantially as described.
19. An internal combustion engine, having, in combination, a cylinder, a piston therein, means for supplying an explosive charge to the cylinder, and auxiliary devices for forming, igniting and imparting a supplementary charge to the cylinder, substantially as described.
20. An internal combustion engine, having, in combination, a working cylinder, a piston therein, means for supplying a main charge of explosive mixture, and mechanism for independently measuring off an auxiliary charge and subsequently imparting said charge to the cylinder during the working stroke of the piston, substantially as described.
21. An internal combustion engine, having, in combination, a working cylinder, a piston therein, an auxiliary combustion chamber, connections including a valve between the chamber and the cylinder constructed and arranged to throw the chamber into communication with the cylinder after the charge in the cylinder has been ignited and the piston has started its working stroke, and means for supplying explosive mixture to the cylinder and to the chamber, substantially as described.
22. An internal combustion engine, having, in combination, a working cylinder, a piston therein, means for forming and igniting a plurality of separate explosive charges and for thereafter imparting them to the cylinder during the same working stroke of the piston, substantially as described.
23. A four-cycle internal-combustion engine, having, in combination, a working cylinder, a piston therein having a working face arranged to draw a charge of explosive mixture into the cylinder above said working face on the suction stroke of the piston, and to compress the charge by the working face of the piston on the next succeeding stroke thereof, an auxiliary combustion chamber, a communication between said chamber and the cylinder, means for controlling said communication, and mechanism independent of the working face of the piston for supplying a charge of explosive mixture to the chamber, substantially as described.
24. An internal combustion engine, having, in combination, a working cylinder, a piston therein, means for forming a plurality of charges of explosive mixture during different strokes of the piston and for imparting them to the cylinder during the same stroke of the piston, substantially as described.
25. An internal combustion engine, having, in combination, a working cylinder, a piston therein, means for forming a plurality of charges of explosive mixture during successive strokes of the piston and for imparting them to the cylinder during the same working stroke, substantially as described.
26. A four-cycle internal combustion engine, having, in combination, a working cylinder closed at each end, a piston therein, valves at one end of the cylinder for controlling the admission and exhaust gases to and from the cylinder, connections between the cylinder on opposite sides of the piston, and means for rendering said connections operative or inoperative at the will of the operator, substantially as described.
27. A four-cycle internal-combustion engine, having, in combination, a working cylinder closed at each end, and having a port located to be uncovered by the piston during its working stroke, a piston in the cylinder, means for supplying gaseous mixture to each end of the cylinder, and connections between said port and the end of the cylinder toward which the piston moves on its working stroke, substantially as described.
28. An internal combustion engine, having, in combination, a working cylinder closed at each end, a piston therein, means for compressing separate charges of explosive mixture at each end of the cylinder during different strokes of the piston, and for imparting them to the same end of the cylinder, substantially as described.

In testimony whereof I affix my signature, in presence of two witnesses.

ERASTUS E. WINKLEY.
